Primary Examiner — Thomas Johannes*Assistant Examiner* — Katrina Gonzalez(74) Attorney, Agent, or Firm — Shook, Hardy & Bacon L.L.P.(57) CLAIM

The ornamental design for a pant, as shown and described.

DESCRIPTION

FIG. 1 is a left front perspective view of a pant according to the present design;

FIG. 2 is a front view thereof;

FIG. 3 is a right side view thereof;

FIG. 4 is a left side view thereof; and,

FIG. 5 is a back view thereof.

The evenly spaced broken lines shown in the drawings are for environmental purposes only and form no part of the claimed design.

The long and short broken lines depict the boundaries of the claim and form no part thereof. These boundaries do not exist in reality in the article embodying the design. It is understood that the claimed design extends to these boundaries but does not include the boundaries.
